UNITED STATES PATENT OFFICE.

FREDERICK RICHARD SIMMS, OF LONDON, ENGLAND.

MEANS FOR STARTING MOTOR ROAD-VEHICLES.

1,090,109.

Specification of Letters Patent. Patented Mar. 10, 1914.

Application filed July 14, 1913. Serial No. 778,974.

To all whom it may concern:

Be it known that I, FREDERICK RICHARD SIMMS, a subject of the King of Great Britain, residing at 191 Wardour street, Oxford street, London, England, have invented new and useful Improvements in Means for Starting Motor Road-Vehicles, of which the following is a specification.

My invention relates to improvements in starting motor road vehicles.

In the specification of application Serial No. 679044, filed Feb. 21, 1912, there is described a magneto-electric machine the magneto of which has two pairs of pole-pieces, between one of which there rotates an armature for generating lighting current, and between the other pair of which there rotates an armature for generating ignition current.

Now, the object of my present invention, is to provide means whereby this machine can be utilized as a motor for starting motor road vehicles, and to this end I employ that armature of the machine which is used for generating the lighting current as a motor, current being supplied thereto from the usual accumulators and the rotation thereof being transmitted to the crank-shaft of the vehicle motor through the medium of suitable gearing. In the case where the lighting armature is driven directly from the ignition armature of the double armature magneto-electric machine, the transmission between the two armatures may be of the free-wheel type, so that the lighting armature can be driven from the accumulators as a motor for starting purposes as above described, without affecting the ignition armature which remains inoperative until it is driven by the petrol motor in the usual manner.

To enable my invention to be fully understood I will describe it by reference to the accompanying drawing, in which:

Figure 1 is a sectional side elevation of a magneto-electric machine of the kind described in the specification of application Serial No. 679044, provided with the means for starting according to the present invention. Fig. 2 is a diagrammatic view illustrating the connections between the magneto machine and the accumulators as hereinafter described. Fig. 3 is a detail view showing part of the magneto illustrated in Fig. 1 and illustrating one method of connecting the same with the cam shaft and crank shaft of an engine. Fig. 4 is a detail view showing the arrangement of the gearing and illustrating the free wheel clutch mechanism.

a represents the magneto magnets, *b* the ignition armature and *c* the lighting armature, the armature *b* being keyed upon the spindle *d*, which is driven by an internal combustion engine in connection with which the magneto-electric machine is fitted. The armature *c* is mounted upon the spindle *e* and is driven from the spindle *d* through the medium of the toothed wheels *d*¹ and *e*¹, the wheel *d*¹ being connected to the spindle *d* through the medium of a free-wheel clutch.

The spindle *e* of the lighting armature *c* has mounted upon it the free-wheel sprocket wheel *f* which is in connection by means of a chain, with a sprocket-wheel upon the crank shaft of the engine or a shaft driven thereby.

The lighting armature *c* is in electrical connection, as shown in Fig. 2, with a secondary battery or set of accumulators *g*, the circuit containing the double pole switch *h* by means of which it can be broken or made as desired.

With this construction it will be obvious that when the internal combustion engine is running normally, the spindle *d* is driven so as to rotate the armature *b* and through the medium of the toothed gearing *d*¹, *e*¹, the armature *c*, thus providing both current for the ignition of the explosive charges in the engine and lighting current from the armature *c*. When, however, it is desired to employ the magneto machine as a means for starting the internal combustion engine then the circuit connecting the armature *c* with the battery *g* is made by means of the double pole switch *h*, whereupon the said armature *c* is rotated so that the spindle *e* is revolved, the armature *b*, however, remaining inoperative by reason of the free-wheel clutch connecting the spindle *d* and wheel *d*¹. The rotation of the spindle *e* revolves the sprocket-wheel *f*, the motion of which is transmitted to the crank-shaft of the engine which is thus started. As soon as the said crank-shaft is set in motion and the engine started the spindle *d* of the ignition arma-

ture b is also rotated, whereupon the necessary current for ignition sparking is provided.

In Figs. 3 and 4 I have shown one arrangement for connecting the magneto hereinbefore described with the cam shaft and crank shaft of an explosion engine, the parts of the magneto being lettered as in Fig. 1. k represents the engine cam shaft which is, 5 in this instance, directly connected with the magneto shaft d by means of a suitable coupling l of any desired character. m represents the crank shaft of the engine which is provided with a sprocket wheel n which is 10 connected by chain o with the sprocket wheel f , loosely mounted on the shaft e of the lighting armature c , the said chain being shown in dotted lines in Fig. 3 and in full lines in Fig. 4. In Fig. 4 the free wheel connection between the shaft e and the sprocket wheel f is shown, the shaft e being provided with a clutch hub e^2 provided with toothed peripheral portions carrying clutch balls e^3 , the said hub and balls being free 15 to rotate within the sprocket wheel f in one direction only. A portion of the hub e^2 is broken away and illustrated in section in this figure. I have similarly shown the free wheel connection between the shaft d and 20 the driving gear d' in this figure, the shaft d being provided with a clutch hub d^2 shown partly broken away to illustrate the toothed portions thereof, and clutch balls d^3 are interposed between the teeth and the gear 25 wheel d' . These free wheel connections are well known and may be of any usual or preferred construction. It will be seen from these figures that by switching current from an external source into the armature c the 30 shaft e will be caused to rotate in the direction of the arrow x in Fig. 4, thus driving the sprocket wheel f through the chain and sprocket wheel n , turning the crank shaft to start the engine. The crank shaft will be 35 connected with the cam shaft k or second motion shaft of the engine in the usual manner. As the armature c begins to rotate, it will necessarily turn the gear wheel d' in the direction of the arrow y adjacent there- 40 to, thus permitting the wheel to be rotated freely without operating the magneto armature b . As soon as the engine shaft begins to rotate, the cam shaft k will rotate the shaft d of the armature b in the direction of 45 the arrow y , Fig. 4, thus rotating the clutch hub d^2 and causing the balls to clutch it to the gear wheel d' , thus driving the gear e' and the armature c at a higher rate of speed. This causes the clutch hub e^2 to ro- 50 tate with respect to the sprocket wheel f , which nevertheless remains connected with the sprocket wheel n .

In the accompanying drawings, p represents the contact breaker for the primary

circuit of the armature b and q represents the distributor. These parts, however, are of well known construction and I have therefore not particularly described or illustrated the same in detail.

Claims:

1. In a magneto electric machine, the combination with permanent magnets, of two pairs of pole shoes carried thereby, a generating armature provided with windings specially adapted for the production of ignition current and located between one pair of pole shoes, an independent armature provided with windings specially adapted for the generation of lighting current located between the other pair of pole shoes, 75 means for positively driving both of said armatures simultaneously from an engine shaft, means connected with the shaft of the lighting armature for positively driving the crank shaft of the engine, and means 80 for connecting the lighting armature with an exterior source of current, whereby it may be employed as a motor for starting the engine.

2. In a magneto electric machine, the combination with permanent magnets, of two pairs of pole shoes carried thereby, a generating armature provided with windings specially adapted for the production of ignition current and located between one pair of pole shoes, an independent armature provided with windings specially adapted for the generation of lighting current located between the other pair of pole shoes, 90 means for positively driving both of said armatures simultaneously from an engine shaft, means connected with the shaft of the lighting armature for positively driving the crank shaft of the engine, and means 95 for connecting the lighting armature with an exterior source of current, whereby it may be employed as a motor for starting the engine.

3. In a magneto electric engine, the combination with permanent magnets, of two 100 pairs of pole shoes carried thereby, a generating armature provided with windings specially adapted for the production of ignition current and located between one pair of pole shoes, an independent armature provided with windings specially adapted for the generation of lighting current located 105 between the other pair of pole shoes, means for driving the ignition armature from an engine shaft, driving connections between 110 the shaft of said armature, constructed to start the engine, and whereby the engine will positively drive both armatures when running.

3. In a magneto electric engine, the combination with permanent magnets, of two 115 pairs of pole shoes carried thereby, a generating armature provided with windings specially adapted for the production of ignition current and located between one pair of pole shoes, an independent armature provided with windings specially adapted for the generation of lighting current located 120 between the other pair of pole shoes, means for driving the ignition armature from an engine shaft, driving connections between 125 the shaft of said armature, constructed to permit the lighting armature to rotate independently of the ignition armature, and

operative connections between the shaft of the lighting armature and the engine crank shaft, constructed to permit the rotation of the crank shaft independently of said armature, and means for supplying current to the

the engine shaft without operating the ignition armature, and whereby the engine shaft may positively drive both of said armatures.
